UNITED STATES PATENT OFFICE.

LEWIS A. DUNHAM, OF KANSAS CITY, MISSOURI, ASSIGNOR, BY MESNE ASSIGNMENTS, TO INTERNATIONAL SEPARATOR COMPANY, OF CHICAGO, ILLINOIS, A CORPORATION OF NEW JERSEY.

MAGNETIC SEPARATOR.

No. 823,492.

Specification of Letters Patent.

Patented June 12, 1906.

Application filed December 8, 1902. Serial No. 134,286.

To all whom it may concern:

Be it known that I, LEWIS A. DUNHAM, a citizen of the United States, residing at Kansas City, in the county of Jackson and State of Missouri, have invented a certain new and useful Improvement in Magnetic Separators, (Case No. 1,) of which the following is a full, clear, concise, and exact description, reference being had to the accompanying drawings, forming a part of this specification.

This invention relates to a magnetic separator of the type in which the material to be separated is passed between a movable carrier, such as a rotating cylinder, and an opposing magnet-pole, the carrier having magnetic teeth or other means for producing convergences of the lines of force toward its surface, said carrier and pole-piece being so disposed that the more permeable particles of material in the mixture are carried into a path divergent from the less permeable particles, which are allowed to fall away.

The object of this invention is to produce a more effective separation, especially in treating materials of very low permeability, and the improvement lies in the combination with such a separator of means for maintaining the maximum magnetic flux substantially undiminished through an extended range of movement of the materials undergoing separation below and beyond the point where the unattracted material is first free to fall away from the attracted material. As an example of such means there may be provided in combination with a hollow separating-cylinder and a magnet-pole facing the outer side thereof a second magnet-pole inside the cylinder and offset with respect to said outer pole, so as to distort downwardly the magnetic flux from said outer pole and concentrate the same upon the cylinder along a segment which lies below and beyond the segment immediately facing said outer pole. In such construction the rotation of the cylinder will therefore move the flux convergences at its surface diagonally with respect to a line joining the magnetic centers of the two pole-pieces. The result is that after the unattracted material is free to fall the attracted material even of very low permeability is held by the undiminished magnetic flux in a path divergent from said falling unattracted material until it has passed

beyond a point where a divider may maintain the separation. In other words, the magnetic field is extended in the direction of movement of the magnetic teeth carrying the attracted material, so as to greatly increase the distance through which any particular tooth may be moved without materially reducing the flux through such tooth, thus holding the attracted material until it is widely separated from the material not attracted.

In the accompanying drawings, Figure 1 is a side elevation of the separator. Fig. 2 is a sectional plan view thereof, taken on line 2-2 of Fig. 1. Fig. 3 is a sectional elevation taken on line 3-3 of Fig. 2, and Fig. 4 is an enlarged sectional view diagrammatically illustrating the distribution of the effective magnetic field.

The same reference characters designate the same parts in all the figures.

The separator consists in its elements of a cylinder mounted to rotate between opposing magnet-poles. In the form shown the cylinder is hollow, and a magnet 4 is mounted inside said cylinder, extending diametrically across the same and having its pole-faces 5, 6 facing the inner periphery thereof. The energizing-winding 9 is shown as wound upon the inner magnet 4 between said pole-faces 5, 6. An iron yoke-piece 1 surrounds the separating-cylinder and is provided with poles 23, 24, facing the opposite sides thereof.

As will be noted, the inner magnet 4 is angularly disposed with reference to the outer pole-pieces 23, 24, so that the inner pole-face 5 is offset with respect to the outer pole-piece 23 and has the effect of distorting downwardly the magnetic flux of said outer pole, as shown most clearly in Fig. 4. The magnet-core 4 is supported by an angularly-adjustable shaft 7, a set-screw 8 being provided to hold the shaft and core in adjustment.

The separating-cylinder is made up of a framework or cage comprising transverse rods 13, 13, extending between the end plates 10, 10, and segmental plates or laminæ, having teeth or projections 14, 14 on their outer edges, said plates being assembled between the transverse rods 13, 13 to build up the body of the cylinder. It will be noticed that the construction of the cylinder is such as to readily permit the passage of magnetic lines

radially through the body thereof, although the longitudinal gaps between the rows of toothed plates interpose a considerable reluctance to the passage of a magnetic flux 5 circumferentially through the cylinder. The teeth upon the segmental plates are adapted to cause local convergences of the magnetic flux toward the surface of the cylinder built up thereby.

• The cylinder is provided with a pulley 25, by which it may be rotated, the direction of rotation being indicated by the arrow 18 in Fig. 3. The material to be separated is received by a hopper 15 and is fed through the 15 spout 16 thereof onto the surface of the rotating cylinder, which carries the same past the magnet-pole 23. A shield 17 is provided to prevent the materials from being thrown off the carrier centrifugally. Collectors 20 20 and 22 are provided underneath the cylinder to receive the separated products.

The magnet having been energized by current from the dynamo 19 passing through the coil 9, there is set up a magnetic flux radially through the cylinder between the inner magnet 4 and the outer pole-pieces 23 and 24, respectively. The flux is diagrammatically indicated by dotted lines in Fig. 4. The projecting iron teeth cause convergences of the 25 lines of force, as shown. The more permeable particles of material passing over the cylinder are attracted to the teeth 14 and held thereby until they are carried past the dividing-point between the collectors 20 and 30 22, said attracted particles being finally discharged into the collector 22 after having been carried past the region of intense magnetic field. The non-magnetic material, being unattracted by the cylinder, falls over 35 the side thereof into the collector 20.

In machines of the type under consideration in order effectually to separate magnetic materials of low permeability from a mixture containing materials of still lower permeability it is necessary that a very intense magnetic flux be provided and that the attractive force thereof shall be exerted at an efficient angle to the force of gravity so that the unattracted material may fall away 45 from the attracted material. In machines of this character heretofore constructed there has been great difficulty in maintaining a sufficiently intense magnetic flux throughout such an extended range of movement of the 50 attracted material after the non-magnetic material is free to fall that a divider-plate can be placed between the two classes of material. In order to effect a separation, the non-attracted material must be free to fall 55 away from the attracted material, and it has been difficult to establish a magnetic flux of sufficient intensity acting at the required angle to the force of gravity and through a sufficiently-extended range of movement of 60 the materials without placing a magnet-pole 65

in such position as to interfere with the free fall of the unattracted material.

In accordance with the present invention the inner magnet 4 is adjusted to an inclined position, as shown in Figs. 3 and 4, so that 70 the inner pole 5 will face an arc on the inner periphery of the cylinder considerably offset below the arc faced by the outer pole-piece 23. The magnetic flux is thereby distorted downwardly, so as to be concentrated along 75 a considerable arc of the cylinder below the horizontal diameter thereof, while the outer pole-piece 23 does not extend into the path of material falling vertically downward over the side of the cylinder. On account of the 80 downward distortion of the main body of magnetic flux the magnetic teeth carrying the attracted material move diagonally with respect to the mean direction of the flux, and so the magnetic saturation of the teeth is 85 maintained to the required degree through an extended range of movement below and beyond the place of separation—that is, the place where the unattracted material is first free to fall away from the attracted material. 90 By this means the attracted material, even of very low permeability, is held by the carrier until it is carried a considerable distance from the place of separation, this result being accomplished without interfering with the 95 free fall of the material not attracted.

The density of the magnetic flux through the cylinder rapidly decreases in the direction of rotation of the cylinder beyond the lower edge of the pole-piece 5, so that the 100 material attracted to the cylinder is released shortly after passing beyond the arc of its path faced by said pole-piece 5 and falls into collector 22.

The invention claimed is—

1. A magnetic separator comprising a movable separating-carrier having means for causing convergences of magnetic flux toward its surface, a magnet-pole facing said carrier, and means for passing material to be 110 separated downwardly through the air-gap between said carrier and said pole, in combination with means for downwardly distorting the magnetic flux between the pole and said carrier.

2. A magnetic separator comprising a cylinder rotatable upon a substantially horizontal axis, and a magnet-pole facing the side of said cylinder, in combination with means for maintaining a magnetic flux of 120 maximum density between said pole and said cylinder throughout an extended arc on the surface of said cylinder below and beyond the lower edge of said magnet-pole.

3. In a magnetic separator, the combination with a magnetic cylinder mounted to rotate upon a substantially horizontal axis, said cylinder having means for causing convergences of magnetic flux toward its surface, of an opposing magnet-pole facing the side of 125 130

said cylinder and lying outside a vertical plane tangent to said cylinder, and means for distorting the flux from said pole downwardly along the under surface of said carrier.

4. In a magnetic separator, the combination with a hollow cylinder rotatable upon a substantially horizontal axis, of an external magnet pole-piece facing the side of said cylinder, means for passing material to be separated through the gap between said cylinder and said pole-piece, and a magnet-pole facing the inner surface of said cylinder along an arc offset obliquely below the arc faced by said outer pole-piece, whereby the concentrated magnetic flux from the outer pole is distorted downwardly toward the under surface of the cylinder, while a clear space is left below for the free fall of the unattracted material.

5. In a magnetic separator, the combina-

tion with a hollow separating-cylinder, of magnet pole-pieces outside and inside of said cylinder respectively, said pole-pieces being offset with reference to each other.

6. In a magnetic separator, the combination with magnet pole-pieces, of means for causing a convergence in the magnetic flux between said pole-pieces, and means for moving said convergence obliquely with respect to a line joining the magnetic centers of the pole-pieces, said pole-pieces being formed to lie outside a vertical plane extending downwardly from the place at which separation begins.

In witness whereof I hereunto subscribe my name this 6th day of December, A. D. 1902.

LEWIS A. DUNHAM.
